(57) **CLAIM**

The ornamental design for a high pressure cleaner foam sprayer as shown and described.

DESCRIPTION

FIG. 1 is a front, top perspective view of a high pressure cleaner foam sprayer, showing my new design;

FIG. 2 is a rear, bottom perspective view thereof;

FIG. 3 is a front elevational view thereof;

FIG. 4 is a rear elevational view thereof;

FIG. 5 is a left side view thereof;

FIG. 6 is a right side view thereof;

FIG. 7 is a top plan view thereof;

FIG. 8 is a bottom plan view thereof; and,

FIG. 9 is a front, top perspective exploded view of the high pressure cleaner foam sprayer shown in an alternative configuration of use.

The broken lines in the figures are for the purposes of illustrating portions of the high pressure cleaner foam sprayer, and form no part of the claimed design.

1 Claim, 9 Drawing Sheets
